SEWING MACHINE

Harold J. Le Vesconte, Western Springs, Ill., assignor to Union Special Machine Company, Chicago, Ill., a corporation of Illinois

Application August 2, 1932, Serial No. 627,238

7 Claims. (Cl. 112—214)

The invention relates to new and useful improvements in sewing machines, and more particularly to a sewing machine which is adapted for sewing heavy wide sections of fabric in the forming of relatively large articles. In the application filed by Norman V. Christensen and myself, July 25, 1932, Serial No. 624,550 there is shown, described and claimed, a machine for this purpose, which includes a relatively long overhanging arm with a stitching mechanism at the free end thereof, and also a feeding mechanism having feeding members engaging the fabric sections adjacent the stitching point, and also feeding members engaging the fabric sections midway between the base and the free end of the overhanging arm. The present invention is an improvement in the machine of the co-pending application.

An object of the invention is to provide a sewing machine of the above type wherein the feeding elements at the stitching point, and the feeding elements intermediate the base and the free end of the overhanging arm are driven from the same eccentric member on the main shaft, so that the number of actuating parts may be reduced to avoid lost motion and obtain better synchronizing of the feed movements applied to the fabric sections.

In the drawings which show by way of illustration one embodiment of the invention—

Figure 1 is a front view of a machine embodying the improvements;

Fig. 2 is a plan view of the feed actuating devices mounted on the bed of the machine and located beneath the work support;

Fig. 3 is an end view of the machine;

Fig. 4 is a sectional view on the line A—A of Fig. 1; and Fig. 5 is a sectional view on the line B—B of Fig. 2.

The machine embodying the invention includes a supporting bed carrying a work support and a main actuating shaft extending lengthwise of the bed and beneath the work support. Mounted on the bed is an overhanging arm which is secured thereto in any suitable way, and which projects to the forward end of the bed. At the free end of the overhanging arm is a needle head in which the needle bar reciprocates carrying a needle of the stitch forming mechanism. There is a feeding mechanism operating on the fabric sections at the stitching point. There is also a pair of feed rollers located directly in rear of the stitching point which grips and feeds the fabric sections away from the stitching mechanism. There is an

other pair of feed rollers located intermediate the needle head and the base of the overhanging arm, and disposed so as to grip the fabric sections in advance of a line extending at right angles to the line of feed and intersecting said line of feed at the stitching point. The present invention has to do particularly with an actuating means for two pairs of feed rollers. This actuating means includes an eccentric on the main shaft with which an eccentric strap cooperates. The eccentric strap imparts oscillations to a rock shaft, and the rock shaft imparts an intermittent movement through a suitable clutch mechanism to a shaft connected to the feed roller beneath the work support and adjacent the stitching point. This shaft is out of alignment with the shaft carrying the feed roller beneath the work support and disposed midway between the free end and the face of the overhanging arm. There is a driving connection between these two shafts, which as shown, is in the form of a chain, so that the single clutch mechanism operates both feed rollers.

Referring more in detail to the drawings, the bed of the machine is indicated at 1 in the drawings. Mounted on this bed is a work support 2. Also mounted on the bed is an overhanging arm 3 carrying a needle head 4 at the free end thereof. Mounted for reciprocation in the needle head is a needle bar 5 carrying, as shown in the drawings, two needles 6, 6. Cooperating with these needles beneath the work support is a suitable complementary stitch forming mechanism. The material is held on the work support at the stitching point by a presser foot which is of the usual character. There is the usual feed dog operating through slots in the throat plate 2a for feeding the material at the stitching point.

Located in rear of the presser foot are two cooperating feed rollers 7 and 8. The upper feed roller 7 is carried by a bar 7a mounted in suitable lugs in the needle head 4. A spring 7b surrounding the bar 7a yieldingly presses the roller 7 into contact with the material.

The lower feed roller 8 is fixed to a shaft 9 mounted in bearing lugs 10, 10 carried by the bed. Attached to the shaft 9 through a universal connection 10a is a shaft section 11. This shaft section 11 is connected through a suitable universal connection 10a to a shaft 12. The shaft 12 is mounted in bearings 12a, 12a carried by the bed. Attached to the shaft 12 is a clutch drum 13. The clutch drum is given an inter-

mittent rotation by a clutch member freely mounted on the shaft 12 and having the usual form of clutch connection to the drum. This clutch member is oscillated by means of a link 13^a connected to an arm 14 fixed to a sleeve 15 mounted for oscillation on a shaft 16 and held from endwise movement thereon by collars 17, 17. The shaft 16 is mounted in lugs 18, 18 carried by the bed. The arm 14 is slotted, and the link 13^a is connected to a stud attached to the arm and shiftable in the slot, so that the stroke of the arm 14 which is imparted to the clutch member may be varied. Also mounted on the sleeve 15 is an arm 19 carrying a stud 20 to which an eccentric strap 21 is connected. The eccentric strap 21 cooperates with an eccentric 22 on the main shaft 23. Associated with the clutch drum 13 is a clutch member which prevents retrograde movement of the shaft 12.

As the main shaft 23 rotates, the eccentric 22 through the eccentric strap will impart oscillations to the arm 14, and said arm in turn will intermittently rotate the drum 13 and thus impart intermittent rotations to the feed roller 8. The movements of the feed roller 8 are, of course, timed with the movements of the feed dog, so that said feed dog and feed roller operate in synchronism for the feeding of the material to and from the stitching mechanism.

Located midway between the base 3^a of the overhanging arm 3 and the needle head 4 is an auxiliary feeding mechanism including an upper feed roller 24 and a lower feed roller 25. The upper feed roller 24 is mounted in a yoke 26 attached to a presser bar 27. This presser bar slides in lugs 28 and 29 carried by a bracket 30 secured to the overhanging arm. A spring 31 located between the lug 29 and the collar 32 fixed to the bar 27, yieldingly presses the roller 24 into engagement with the fabric section passing beneath the overhanging arm.

The feed roller 25 is fixed to a shaft 33. The shaft 33 is mounted in bearing lugs 34, 35 and 36 carried by a bracket 37 secured by bolts 38 to the upstanding portion 1^a of the bed. The bearing lugs 35 and 36 are located at each side of the feed roller 25 and provide a very firm and durable support therefor. The shaft 33 carries a sprocket wheel 39 at the end thereof. A chain 40 engages said sprocket wheel 39 and also engages a sprocket wheel 41 on the end of the shaft 12.

The same intermittent movements which are imparted to the feed roller 8 from the shaft 12 are imparted through the chain 40 to the shaft 33 and thence to the feed roller 25. The shaft 12 is attached through the universal connections to the feed roller 8, and therefore, does not require accurate alinement with the feed roller shaft. The shaft 12 is also connected through the sprocket chain to the shaft 33, and therefore, does not require accurate alinement therewith.

Both feed rollers are positively driven from the same eccentric, that is, the eccentric 22. Both feed rollers are likewise driven from the same clutch drum, and any slippage in the operation of the clutch drum will be in like manner imparted to both of the feed rollers. By this interconnected driving mechanism for the feed rollers, the number of parts with the lost motion incident thereto is reduced to a minimum, and the movements imparted to the feed rollers are in synchronism and of uniform ex-

tent. The feed rollers 24 and 25 are located so as to engage the material at a point in front of a line at right angles to the main feed and passing through the stitching point. This location of the auxiliary feed rollers relative to the main feeding mechanism and the stitching point, is shown, described and claimed in the companion application aforesaid. The present invention has to do more particularly with the operating mechanism for these feed rollers whereby perfect synchronism of the feeding movements are obtained. The machine is particularly designed for uniting heavy fabric sections. One of the fabric sections is passed beneath the overhanging arm which is very long, so as to accommodate a relatively wide fabric section. The feed rollers 24 and 25 will grip the forward edge of the fabric section slightly before it is reached by the stitching needles, and this enables the placing of the fabric section beneath the arm prior to the placing of the fabric section at the left of the stitching mechanism, as viewed from the front of the machine.

It is obvious that minor changes in the details of construction and the arrangement of the parts of the driving mechanism may be made without departing from the spirit of the invention as set forth in the appended claims.

Having thus described the invention, what I claim as new and desire to secure by Letters Patent, is—

1. In a sewing machine, the combination of a supporting bed, a main shaft, a work support carried by said bed, an overhanging arm having a supporting base attached to said bed, a needle head at the free end of said overhanging arm, a needle bar therein, a needle carried by said needle bar, a feeding mechanism at the needle head, a feeding mechanism intermediate the supporting base and the needle head, each feeding mechanism including a feed roller, an eccentric on the main shaft, an auxiliary shaft, a clutch drum associated therewith, means operated by said eccentric for oscillating said clutch drum and imparting intermittent movements to said auxiliary shaft, devices connecting said auxiliary shaft to one of said feed rollers, a separate shaft carrying the other feed roller, and devices operated by the auxiliary shaft for actuating said separate shaft.

2. In a sewing machine, the combination of a supporting bed, a main shaft, a work support carried by said bed, an overhanging arm having a supporting base attached to said bed, a needle head at the free end of said overhanging arm, a needle bar therein, a needle carried by said needle bar, a feeding mechanism intermediate the supporting base and the needle head, each feeding mechanism including a feed roller, an eccentric on the main shaft, an auxiliary shaft, a clutch drum associated therewith, means operated by said eccentric for oscillating said clutch drum and imparting intermittent movements to said auxiliary shaft, a universal connection between said shaft and one of said feed rollers, a separate shaft supporting the other feed roller, and devices operated by said auxiliary shaft for actuating said separate shaft.

3. In a sewing machine, the combination of a supporting bed, a main shaft, a work support carried by said bed, an overhanging arm having a supporting base attached to said bed, a needle head at the free end of said overhanging arm, a needle bar therein, a needle carried by said

- needle bar, a feeding mechanism at the needle head, a feeding mechanism intermediate the supporting base and the needle head, each feeding mechanism including a feed roller, an eccentric on the main shaft, an auxiliary shaft, a clutch drum associated therewith, means operated by said eccentric for oscillating said clutch drum and imparting intermittent movements to said auxiliary shaft, a universal connection between said shaft and one of said feed rollers, a separate shaft supporting the other feed roller, and a chain and sprocket means for connecting said auxiliary shaft to said separate shaft. 5 80
4. In a sewing machine, the combination of a supporting bed, a main shaft, a work support carried by said bed, an overhanging arm having a supporting base attached to said bed, a needle head at the free end of said overhanging arm, a needle bar therein, a needle carried by said needle bar, a feeding mechanism at the needle head including a pair of feed rollers, one mounted above and the other below the work support, a feeding mechanism disposed intermediate the supporting base and the needle head 10 85
- 20 said and including a pair of feed rollers, one mounted above and the other below the work support, said feed rollers at the needle head being located in rear of the stitching point, and said feed rollers midway of the overhanging arm being disposed so as to engage the fabric in front of a line at right angles to the main feed and passing through the stitching point, a shaft carrying the feed roller beneath the work support at the needle head, an auxiliary shaft in alignment therewith and connected thereto, a clutch drum associated with said auxiliary shaft for imparting intermittent movements thereto, an eccentric member on the main shaft, devices operated thereby for operating the clutch drum, a shaft carrying the feed roller beneath the work support midway of the overhanging arm, said shaft being out of alignment with the auxiliary shaft, and means for imparting intermittent movements from the auxiliary shaft to said last-named feed shaft. 25 90

- 45 110
5. In a sewing machine, the combination of a supporting bed, a main shaft, a work support carried by said bed, an overhanging arm having a supporting base attached to said bed, a needle head at the free end of said overhanging arm, a needle bar therein, a needle carried by said needle bar, a feeding mechanism at the needle head including a pair of feed rollers, one mounted above and the other below the work support, a feeding mechanism disposed intermediate the supporting base and the needle head and including a pair of feed rollers, one mounted above and the other below the work support, said feed rollers at the needle head being located in rear of the stitching point, and said feed rollers midway of the overhanging arm being disposed so as to engage the fabric in front of a line at right angles to the main feed and passing through the stitching point, a shaft carrying the feed roller beneath the work support at the 60 115
- 65 120
- 70 125
- 75 130
- 80 135
- needle head, an auxiliary shaft in alignment therewith and connected thereto, a clutch drum associated with said auxiliary shaft for imparting intermittent movements thereto, an eccentric member on the main shaft, devices operated thereby for operating the clutch drum, a shaft carrying the feed roller beneath the work support midway of the overhanging arm, said shaft being out of alignment with the auxiliary shaft, a sprocket wheel on the end of said auxiliary shaft, a sprocket wheel on the end of the shaft carrying the last-named feed roller, and a sprocket chain running over said sprocket wheels. 85 80
6. In a sewing machine, the combination of a supporting bed, a work support carried by said bed, a main actuating shaft beneath said work support, an overhanging arm having a supporting base carried by said bed, a needle head at the other end of said overhanging arm, a needle bar therein, a needle carried by said needle bar, a feeding mechanism including feed rollers located in rear of said needle, one of said rollers being located beneath the work support and the other being carried by said needle head, a feeding mechanism located intermediate the supporting base and the needle head and including feed rollers, one of which is located beneath the work support and the other of which is carried by the overhanging arm, an eccentric on the main shaft beneath the work support, an auxiliary shaft connected to the feed roller in rear of the needle, means operated by said eccentric for intermittently rotating said auxiliary shaft, and means operated by said auxiliary shaft for rotating the feed roller beneath the work support and intermediate the needle head and the supporting base. 95 90
7. In a sewing machine, the combination of a supporting bed, a work support carried by said bed, a main actuating shaft beneath said work support, an overhanging arm having a supporting base carried by said bed, a needle head at the other end of said overhanging arm, a needle bar therein, a needle carried by said needle bar, a feeding mechanism including feed rollers located in rear of said needle, one of said rollers being located beneath the work support and the other being carried by said needle head, a feeding mechanism located intermediate the supporting base and the needle head and including feed rollers, one of which is located beneath the work support and the other of which is carried by the overhanging arm, an auxiliary shaft located beneath the work support and having a universal connection with the feed roller in rear of the needle, an eccentric on the main shaft, a clutch drum carried by the auxiliary shaft and operated from said eccentric for intermittently rotating said auxiliary shaft, a shaft supporting the feed roller beneath the work support and intermediate the supporting base in the needle head, and a chain and sprocket means connecting said auxiliary shaft to said last-named shaft. 120 105
